ANIMAL FIGURE TOY

Irvin J. Gershen, Springfield, N.J., assignor to Johnson & Johnson, a corporation of New Jersey

Filed Dec. 21, 1965, Ser. No. 265

Term of patent 14 years

(Cl. D34—15)

FIG. 1 is a front view of an animal figure toy showing my design;

FIG. 2 is a front view of the animal figure toy showing my new design in an alternate position.

FIG. 3 is a side view of the animal figure toy shown in FIG. 2;

FIG. 4 is a top view of the animal figure toy shown in FIG. 2; and,

FIG. 5 is a bottom view of the animal figure toy shown in FIG. 2.

I claim:

The ornamental design for an animal figure toy, as shown.
